Primary Examiner—Terry A. Wallace*Attorney, Agent, or Firm*—Leonard Bloom[57] **CLAIM**

The ornamental design of a holder for hex keys, as shown and described.

DESCRIPTION

FIG. 1 is a front elevational view of a one embodiment of holder for hex keys showing our new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a cross-sectional view taken across the lines 7—7 of FIG. 1.

FIG. 8 is a front elevational view of a second embodiment of a holder for hex keys.

FIG. 9 is a rear elevational view thereof.

FIG. 10 is a left elevational view thereof.

FIG. 11 is a right elevational view thereof.

FIG. 12 is a top plan view thereof.

FIG. 13 is a bottom plan view thereof; and,

FIG. 14 is a cross-sectional view, taken across the lines 14—14 of FIG. 8.
